UNITED STATES PATENT OFFICE

98,938

DESIGN FOR A DISPLAY BOX OR THE LIKE

John L. Hawkinson, Hartford, Conn., assignor to
The Arrow-Hart & Hegeman Electric Company, Hartford, Conn., a corporation of Connecticut

Application August 3, 1935, Serial No. 57,925

Term of patent 14 years

To all whom it may concern:

Be it known that I, John L. Hawkinson, a citizen of the United States of America, residing at Hartford, Connecticut, have invented a new, original, and ornamental Design for a Display Box or the like, of which the following is a specification, reference being had to the accompanying drawing, forming part thereof.

Figure 1 is a front elevational view showing, in closed position, a display box or the like embodying my new design.

Fig. 2 is a side elevational view of the box shown in Fig. 1;

Fig. 3 is a top plan view of the box shown in Fig. 1.

I claim:

The ornamental design for a display box or the like, as shown and described.

In testimony thereof I have signed my name to this specification.

JOHN L. HAWKINSON.
